PIVOTED HAND CRIMPING TOOL WITH DIVERGENCE LIMITING MEANS

Walter Labuza, Perth Amboy, N. J., assignor to Buchanan Electrical Products Corporation, Hillside, N. J., a corporation of New Jersey

Application October 24, 1952, Serial No. 316,570

2 Claims. (Cl. 81—15)

This invention relates generally to electrical equipment and more particularly to an improved hand operated tool for mechanically and electrically uniting an electric connector and an electrical conductor.

Electric connectors having a socket portion for the reception of the bared ends of an electrical conductor are well known throughout the electrical industry. One manner of affixing connectors of this general description to the conductors involves swaging or crimping the connector into close intimate contact with the conductor. Various hand operated tools for performing this function, wherein the metallic elements are cold worked, have been introduced into the electrical field.

It is an object of this invention to provide an improved hand crimping tool that can readily lend itself to mass production uses. A very important use of a hand tool of the type described involves its operation under conditions where it is necessary for an operator to mechanically and electrically unite hundreds and even thousands of these connectors with their associated conductors per day. It is accordingly a further object of this invention to provide an improved crimping tool that will reduce operator fatigue to a minimum.

An additional feature of this invention includes the provision of an improved crimping tool that will insure efficient operation and will be economical to manufacture.

Other advantages and objects of this invention will be apparent from a consideration of the ensuing specification and drawings in which:

Fig. 1 is a side elevation of a swaging tool embodying my invention;

Fig. 2 is a partial side elevation of one of the operating handles forming part of the tool;

Fig. 3 is a partial side elevation of the other operating handle;

Fig. 4 is a side elevation, partly broken away for clarity, of the forming pin retainer and components;

Fig. 5 is a section of one handle member taken on line 5—5 of Fig. 2;

Fig. 6 is a side elevation of a bearing pin;

Figs. 7 and 8 are bottom plan and side views respectively of the latch member;

Figs. 9 and 10 are top plan and side views respectively of the lever member; and

Figs. 11, 12 and 13 are side views, partly broken away, illustrating the various operating positions of the latch and lever mechanism.

This invention relates to an improved crimping tool of the type described in United States Letters Patent 2,467,012 issued April 12, 1949 to Fritz Deusche and assigned to the Buchanan Electrical Products Corporation. Tools of this general classification include two handle members 10 and 12. The first handle 10 is channel shaped in section and has an enlarged extremity 14 having aligned apertures 16 approximately in the center of the enlarged portion and aligned openings 18 spaced radially from aperture 16. Handle 12 has at one extremity thereof an enlarged portion 20 similar to 14 of handle 10. The member 12 is preferably composed of

2
cast iron or the like and has an opening 22 defined by a series of interconnected cam surfaces 24. Also disposed integral with the exterior surface of the enlarged extremity is a stepped abutment member 26.

5 A cylindrical retainer member for supporting and guiding a plurality of forming pins is indicated at 28. The retainer has an axial bore 30 and a plurality of smaller bores 32 parallel to bore 30 spaced equidistant therefrom. Circular forming pin passageways 34 extend radially from bore 30, midway between the top and bottom surfaces of the retainer and include an enlarged portion 36 and a constricted portion 38. A shoulder 40 is formed at the juncture of the enlarged portion and the constricted portion. Provided in each passageway 34 is a forming pin 42 including a head portion 44, an intermediate shank portion 46 and a forming extremity 48. Also located in the enlarged section 36 of the passageway is a spring member 50, one end of which bears against shoulder 40 and the other end against shoulder 52 formed by the juncture of members 44 and 46 so as to urge the pin 42 normally outward from the bore 30.

In assembling the tool, retainer member 28 is placed in opening 22 so that the head portions of the forming pins are in engagement with cam surfaces 24. Enlarged end 20 of handle member 12 is then inserted between the parallel sections 14 so that openings 18 and 32 are in alignment. Conventional fastening units such as bolts are then inserted through the aligned openings and are attached to the tool by nuts or the like. It may now be readily appreciated that relative movement between the unattached extremities of the handle members will cause cam surfaces 24 to engage the head portions of the forming pins 42 forcing the pins downwardly across the opening 30 against the action of spring member 50.

Therefore when it is desired to unite a connector with the bared ends of an electric conductor, the connector is inserted through opening 16 until it is supported by a conventional stop element (not shown), the ends of the conductor are then placed in the conductor receiving portion of the connector and the forming pins caused to converge into engagement with the connector in response to relative convergent movement of the handles.

Swaging tools of this general description are used to unite connectors of various sizes with their associated conductors. For example it is necessary for the tool to unite a No. 16 connector with a conductor as well as a No. 8 connector with its associated conductor. Inasmuch as the diameter of the conductor receiving socket of a No. 16 connector is much less than a diameter of the conductor accommodating socket of a No. 8 connector it would be convenient to provide means for restricting the divergent movement of the handles 10 and 12 which in turn would restrict the amount of the divergent movement of the pins 42 when the tool is being used to unite a quantity of No. 16 connectors with their associated conductors. 55 This in turn would limit the amount of convergent movement of the handles necessary to join the elements. This feature becomes important when the tool is utilized on a production line where hundreds of connections must be made in a relatively short time. An operator working on such a line is called upon to grasp and squeeze the handles together as each connection is made. Limiting the extent of the normal divergent movement of the handles under the influence of spring 50 in turn limits the amount of convergent movement necessary to effect the next succeeding connection which in turn increases the efficiency of the operator. An additional advantage in restricting the divergent movement of the pins, when small size connectors and conductors are joined, is the elimination of the tendency of the smaller size connector to slip completely through bore 30, which of necessity has a diameter large enough to accommodate larger size con-

nectors. This is true because portions of the pins project partially across the opening defined by bore 30 and thereby impede the passage of the connector. In fact the smaller connectors tend to locate themselves centrally of the bore in a position contiguous to the forming portions of the pins due to the presence of the pin extremities.

One arrangement for selectively limiting the normal divergent movement of the handles includes a bearing pin 60 having a particular configuration as illustrated in Fig. 6. One end portion 62 of the bearing pin 60 is circular in section and has a conical socket 64 for a purpose to be later described. Axially spaced from portion 62 is a section 66, approximately square in cross section, integrally connected to section 66 is a second circular portion 68, slightly larger in diameter than end portion 62 and extending from one extremity of portion 68, and integrally connected therewith, is a portion 70 also square in cross section. A latch member 72, shown in Figs. 7 and 8 has two parallel sides 74 and 76, each containing aligned openings 78 having a square configuration. The sides 74 and 76 are joined by a flat portion 80. At one end of the side members 74 and 76 there is provided a portion of reduced length 82. This portion is defined by a shoulder 84, so that the latch has at one end thereof a stepped configuration. Provided in handle member 10 are two oppositely disposed apertures 86 and 88, the former having a diameter slightly larger than the diameter of pin end portion 62 and the latter having a diameter approximately equal to bearing pin portion 68.

In assembling the bearing pin and latch elements with the tool, the latch is first placed in the U-shaped handle member 10 with openings 78 in alignment with apertures 86 and 88 and the stepped extremity directed toward the head or operating end of the tool so as to engage abutment 26 on handle 12. Bearing pin 60 is then inserted through aperture 88, aligned openings 78 in the latch member 72 and aperture 86 in that order until the end portion of section 66 of the pin frictionally engages that portion of handle 10 defining aperture 88. The bearing pin is designed so that the end portion 62 now protrudes slightly beyond the outside surface of handle 10. Any tendency for the bearing pin to move axially in reverse of the direction of insertion may be prohibited by forcibly inserting a sharp ended tool (not shown) in conical recess 64 so as to radially expand the end portion 62.

Extending from the opposite outside surface of the handle is section 70 of the pin. A lever 90, having a square opening 92 in conformance with section 70 is keyed onto the pin at this extremity. One end of the lever 90 has an upset portion 94 formed by "pinching" the end part of the lever upwardly out of the plane of the lever. This upset portion serves as a handle for an operator to grasp with his fingers in order to move the lever. A protuberance 96 formed by indenting the upper surface of the lever cooperates with three spaced recesses 98 on the surface of the handle to maintain the lever in a predetermined position.

When the lever 90 is positioned as shown in Fig. 11, the latch 72 is positioned so that its unattached end will engage the foot of abutment 26 after a minimum amount of divergence of the handles 10 and 12. Further divergence is prevented.

If the lever 90 is positioned as shown in Fig. 12, the latch 72 will be positioned so that its shoulder 84 will engage the outer edge of the abutment 26 after a greater amount of divergence of the handles 10 and 12, thus preventing further divergence.

When the lever 90 is positioned as shown in Fig. 13, the latch 72 is positioned so that it will not engage the abutment 26. Thus, the latch 72 will not limit the divergence of the handles 10 and 12.

Thus there is provided a means for adjusting within certain predetermined limits the relative divergent movement of the forming pins in a swaging tool of the type described.

It is not my intention to limit the use of my invention to hand operated swaging tools. Various applications of the principles herein stated will suggest themselves to those skilled in the art without departing from the spirit or scope of the invention.

I claim:

1. A tool for crimping an electrical connector to a conductor, comprising a first handle having a channel shaped enlargement, a second handle having an enlarged portion nesting within and pivotally connected with said channel shaped enlargement, a plurality of forming pins, means supporting and guiding said pins, means for moving said pins in convergent and divergent directions in response to a corresponding movement of the handles, an abutment on said second handle within said channel shaped enlargement of said first handle, adjustable means for limiting divergent movement of said handles, said adjustable means including an abutment engaging latch, a pin pivotally connecting said latch to said first handle at a point separated from the pivotal connection of said first and second handles and within the channel shaped enlargement of said first handle, means including three spaced recesses on the outer surface of said first handle positively defining first, second and third definite positions of said latch and a lever keyed to said pin on the outer surface of said first handle whereby said latch is movable, said lever having a portion adapted to selectively engage said recesses positively to hold said latch selectively in one of said positions, said latch and said abutment being adapted for engagement when said latch is in said first and second positions, so that a greater amount of divergence of said handles is permitted when said latch is in said second position than when in said first position, and when said latch is in said third position said adjustable means permits a maximum amount of divergence of said handles.

2. A tool for crimping an electrical connector to a conductor, comprising a first handle having a channel shaped enlargement, a second handle having an enlarged portion nesting within and pivotally connected with said channel shaped enlargement, a plurality of forming pins, means supporting and guiding said pins, means for moving said pins in convergent and divergent directions in response to a corresponding movement of the handles, an abutment on said second handle within said channel shaped enlargement of said first handle, adjustable means for limiting divergent movement of said handles, said adjustable means including an abutment engaging latch, a pin pivotally connecting said latch to said first handle at a point separated from the pivotal connection of said first and second handles and within the channel shaped enlargement of said first handle, means including two spaced recesses on the outer surface of said first handle positively defining first and second definite positions of said latch and a lever keyed to said pin on the outer surface of said first handle whereby said latch is movable, said lever having a portion adapted to selectively engage said recesses positively to hold said latch selectively in one of said positions, said latch and said abutment being adapted for engagement when said latch is in said first position to permit a predetermined amount of divergence of said handles and so that when said latch is in said second position said adjustable means permits a maximum amount of divergence of said handles.
